WATCH CLEANING MACHINE

Harold G. Foote, Fontana, Wis., assignor to The
George W. Borg Corporation, Chicago, Ill., a
corporation of Delaware

Application October 7, 1950, Serial No. 188,929

28 Claims. (Cl. 134—57)

1

The present invention relates in general to cleaning apparatus, and more in particular to apparatus which is adapted for use in cleaning small parts such as the parts of watches and clocks. The general object of the invention may be stated to be the provision of a new and improved watch cleaning machine, adapted primarily for cleaning watch parts but capable of use in cleaning any small mechanical parts of a similar nature.

A feature of the invention is a watch cleaning machine which is substantially completely automatic in operation, the attention of an operator being required only for the purpose of placing the parts in the machine, starting the machine, and removing the parts after they are cleaned and dried.

The foregoing and other features will be described more in detail in the ensuing specification, reference being had to the accompanying drawings, in which—

Fig. 1 is a vertical section through a watch cleaning machine embodying the invention, on the line 1—1, Fig. 2;

Fig. 2 is a horizontal section on the line 2—2, Fig. 1;

Fig. 3 is a partial section on the line 3—3, Fig. 1;

Fig. 4 is a horizontal section on the line 4—4, Fig. 1;

Fig. 5 is a partial section on the line 5—5, Fig. 1, showing the mechanism for starting and stopping the spinning drive for the parts basket;

Fig. 6 shows part of the link 116 in the position in which it appears in Fig. 1, the parts in front of the link being cut away on the line 6—6, Fig. 5;

Figs. 7 to 10, inclusive, are detailed views, partly diagrammatic, which show the raising and lowering mechanism for the parts basket at different stages of operation;

Fig. 11 is a view of the lifting cam and associated parts shown in Fig. 8 as seen from above and looking in a direction which is perpendicular to the lifting lever 150.

Fig. 12 is a partial section on line 12—12, Fig. 3, showing details of the lost motion device; and

Fig. 13 is a diagrammatic circuit drawing showing the electrical wiring of the machine.

Referring to Figs. 1 and 4 of the drawings, the machine includes a tank which serves as a container for the jars of cleaning and rinsing fluids and also functions as a frame for supporting various parts of the machine. This tank comprises a bottom or base 10, side walls 11 and 12,

2

a rounded front wall 13, and a rear wall 14 which is spaced inward a short distance from the rear end of the base. There is a downwardly extending flange or rim 16, all around the base, as indicated in Fig. 1. This rim has a foot 17 in front and two feet such as 18 at the rear which rest on the table or bench where the machine is installed.

A partition 15 extends from the front wall 13 to the rear wall 14 and forms an enclosure for the jars 20, 21, and 22, which rest on ribs formed on the base 10 as shown. These jars may be made of any suitable material, such as stainless steel, for example. Jar 20 contains a washing solution suitable for the purpose, containing soap or a detergent, for example, or any desired cleaning fluid. Jar 21 contains a rinsing fluid such as carbon tetrachloride, for example, while jar 22 contains a second rinsing fluid which may be alcohol, for example.

For the purpose of heating the cleaning and rinsing fluids the enclosure or tank proper in which the jars are located is filled with water up to a couple of inches or so of the top and an electrical heating element 23 is mounted on the base 10 against the lower surface thereof. This heating element may be of any suitable type and is connected in circuit with a thermostatic switch 24, also mounted on the base 10. The connections are shown in Fig. 13 and will be described at a later point in the specification.

Between the partition 15 and the wall 12 of the tank there is a compartment 28, in which air may be heated by contact with the partition and the adjacent walls. An opening 29 is provided to admit air from beneath the base 10. One or more baffles (not shown) may be provided to divert the flow of air horizontally, if desired.

The front wall 13 and the side walls 11 and 12 of the tank are provided with an external horizontal rib 30 near the bottom and a flange 31 at the top. This rib and the flange are connected at the rear by external vertical ribs 32 and 33. The outside casing 34 may be made of sheet metal and is supported on ribs 30, 32, and 33 and flange 31 in spaced relation to the walls of the tank, as shown in Figs. 1 and 4.

The rear wall 14 of the tank has a wide flange 35 at the top which connects the side walls 11 and 12 and with the flange 31 forms a continuous surface on which the cover plate 36 is supported. The cover plate is secured against displacement by means of the hinges 37 and 38. The hinge 37 comprises a short piece of rod having a section

of reduced diameter which passes through a hole in the cover plate and is secured thereto by a nut 40, and a curved section which extends downward through a hole in the flange 35. The hinge 38 is the same. These hinges make it possible to raise the cover plate by rotating it about the rear edge 39 as a fulcrum, as can be seen clearly enough from Fig. 1. A nut 41 at the end of the hinge rod 37 and a similar nut on hinge rod 38 limit the extent to which the cover may be rotated to about 90 degrees, which is sufficient to expose the interior of the tank and the jars 20-22.

The cover plate 36 is provided with four openings indicated by reference characters 42 to 45, respectively. The first three of these openings are in alignment with the jars 20, 21, and 22, respectively, and are slightly smaller in diameter. The fourth opening 45 is above the warm air compartment 28. Each opening is surrounded by a raised rim such as the rim 46 which surrounds the opening 44, and all four rims are joined by and merge into a circular rim 47. The rim 47 is provided with four equally spaced notches which are indicated at 48, 49, 50, and 51, as shown in Fig. 2.

The reference character 52 indicates a disc, preferably of metal, which rests on the rim 47, also the rims such as 46, and effectually closes all the openings in the cover plate 36 except one. The disc 52 has an opening 53, shown in Fig. 2 as being in alignment with the opening 42, whereby this opening and the jar 20 beneath it are exposed and rendered accessible. The disc 52 is rotatable to expose the other openings in the cover plate 36 successively, as will be described later on.

Mounted on the cover plate 36 there is a rotatable frame which is indicated generally by the reference character 55 in Fig. 1. This frame may be an aluminum casting and comprises the top 56, the depending sides 57 and 58, and the web 59 which connects the sides at the right. The frame is tapered at the left, as can be seen in Fig. 2, and the sides 57 and 58 are merged to form a rounded end 60. The top 56 slopes upward to the right, but at the rounded end of the frame it is horizontal and is provided with an integrally formed cylindrical bearing member 61. This bearing member is fitted with bushings by means of which it is rotatably supported on the post 62, extending upward from cover plate 36 at the center of the circular rim 47. The post 62 is secured to the cover plate in any suitable manner, as by means of a screw 63. From the foregoing it will be understood that the frame 55 is rotatable in a horizontal plane about the post 62 as an axis.

The stud 64 may be formed integrally with the top 56 of the frame 55 and extends downward through a hole in the disc 52. A central opening in the disc provides room for the bearing member 61 and the helical spring 65 which surrounds it. One end of this spring is hooked around the stud 64, while the other end is secured to the cover plate 36 by means of the screw 67. The spring 65 tends to rotate the frame 55 in a clockwise direction as seen in Fig. 2. The frame is locked in the position in which it is shown by means engaging the notch 48 in rim 47, as will shortly be described.

A short stud 66 extends downward from the rounded end 60 of the frame and through a slot in the disc 52. The studs 66 and 64 serve to keep the disc 52 in position on rim 47 and also serve to

rotate the disc whenever the frame 55 is rotated. That is, the disc rotates with the frame.

Near the right hand end of the frame 55 there are two upwardly extending members 67 and 68 which constitute inwardly offset extensions of the side members 57 and 58, respectively. The member 68 is seen in Fig. 1 and both members are shown in Fig. 3. These frame members support the shafts 71 and 72. The frame member 67 is square on top, while frame member 68 is provided with an upwardly extending projection 73 the purpose of which will be explained presently.

The reference character 73 indicates a motor which may be of any suitable type adapted to run on commercial alternating current. Preferably, however, a so-called "universal" motor is used, adapted to operate on either alternating or direct current. The motor is enclosed in a housing which comprises the two sides 74 and 75, the rear end 77 connecting the two sides, and the top 76. The side 74 is seen in elevation in Fig. 1, the lower outline being shown by a dotted line where it is obscured by other parts. Side 75, which is cut away in Fig. 1, is identical with side 74. The two sides 74 and 75 are outside the frame members 67 and 68 and extend parallel to each other to a point to the left of motor 73 where they converge as indicated in Fig. 2 and again extend parallel to each other to the end of the housing. The top 76 of the housing has a large opening therein to give access to the motor and associated parts. To the left of this opening the top curves downwardly, forming a nose having a rounded upper surface, as indicated in Fig. 1.

The opening in the top 76 of the motor housing is closed by a cover 78, which is held in place by a screw 79 and two similar screws (not shown) which pass through the cover and are threaded into tapped holes in the top 76 on opposite sides of the opening.

The motor housing is pivotally mounted on the frame members 67 and 68 by means of the shaft 72 which has bearings in the sides 74 and 75 of the housing and also in the frame members. This shaft is rotated by motor 73 as will presently be described and also functions as a pivotal support for the motor housing.

The motor 73 is supported in the housing by means of a bracket of rather complicated construction which will now be described. The bracket comprises a flat ring 81 which is secured to the end of the motor frame by two screws as shown in Fig. 3, two forwardly extending bearing members 82 and 83 which support the horizontal shaft 84, two members 85 and 86 which extend to the right from the base of the bearing member 83 and support the vertical shaft 87, and the flange 88 which connects the members 85 and 86. The flange 88 rests against the side 74 of the motor housing to which it is secured by means of screws as shown. These parts are all shown clearly in Fig. 3 and some of them also in Fig. 1.

The motor shaft is indicated at 95 and carries the worm 89, which is in mesh with the worm wheel 90 on shaft 84. The motor therefore drives the shaft 84 by means of worm 89 and worm wheel 90. Shaft 84 drives the shaft 87 by means of the worm 91 and the worm wheel 92, the former being carried on shaft 84 and the latter on shaft 87. The shaft 87 is rotatably supported by bearings in members 85 and 86 and carries the worm 93 which is in mesh with the worm wheel 94 on shaft 72, whereby the latter shaft is driven from shaft 87. The shaft 84 rotates at a speed of about 230 R. P. M., while shaft 72 rotates at a speed of 75 about 1 rotation in five minutes. These speeds

are not at all critical, but have been found to be satisfactory.

Mounted at the left hand end of the motor housing there is a supporting bracket 99 for the washing basket 108. The bracket 99 is preferably a metal casting and comprises the vertical side members 101, 102, and 103 and the lower end member 100. A shaft 104 extends through the sides 74 and 75 of the motor housing and through bearings in the side members 102 and 103 of the bracket 99, whereby the latter is pivotally supported on the motor housing.

The cylindrical bearing member 105 extends downward from the end member 100 of bracket 99 and is fitted with bushings as shown for rotatably supporting the shaft 112. The hub 106 of the short cylindrical flanged member 107 is secured to the lower end of shaft 112 by means of a set screw 110. The hub 106 has an upwardly extending skirt 111 to protect the lower bearing of shaft 112 against the entrance of cleaning or rinsing fluid when the machine is in operation. The washing basket 108 may be of any suitable type. As indicated in Fig. 1 it comprises an upper ring 113 which is removably secured to the flanged member 107 by bayonet joints such as 109, and a depending skeleton frame 115 which supports the parts containers such as 114 made of wire screen cloth. There may be three of these containers stacked one above the other as indicated.

The basket 108 is lowered into and raised out of the jars such as 20 by rotation of the motor housing on the shaft 72. The basket is shown in its lowered position in Fig. 1, where it is wholly immersed in the fluid in jar 20. This position is determined by the engagement of roller 140 with the projection 70 on frame member 68, which limits the rotation of the motor housing in a counterclockwise direction. The roller 140 is mounted on shaft 141 which is an extension of shaft 84, Fig. 3. The shaft 141 is slightly eccentric or off center with respect to shaft 84 so that rotation of the latter shaft produces an oscillatory movement of the motor housing about shaft 72. While the eccentricity of shaft 141 is small, it is sufficient to produce a substantial oscillatory motion at the left hand end of the motor housing, where the bracket 99 and basket 108 are supported. The motion of the basket may be about $\frac{1}{8}$ inch, for example.

Since the bracket 99 and the basket 108 are suspended from shaft 104, they tend to remain in a vertical position when the basket is raised or lowered by rotation of the motor housing on shaft 72. However, it is desirable to positively maintain the vertical alignment in order to insure safe passage of the basket through the openings such as 42 and to this end a link 116 is provided. This link extends lengthwise of the motor housing as indicated in Fig. 1 and at its right hand end it is connected to the shaft 71 by means of a hub 119 and set screw as shown in Fig. 3. The left hand end of the link 116 is provided with a bearing hub 118 which is rotatable on the shaft 117. This shaft extends through the sides 102 and 103 of the bracket 99 and through the link 116 and its bearing hub 118 and is similar to shaft 104 immediately above it. The shafts 72 and 71 and shafts 104 and 117 define a parallelogram. The shafts 72 and 71 are fixed in vertical alignment. It follows that when the motor housing is rotated about shaft 72 to raise or lower the basket 108 the shafts 104 and 117 remain in vertical alignment also.

In order to partly balance the weight of the motor housing and the parts supported thereon a spring 27 is provided and is tensioned between a pin fixed to the link 116, Fig. 1, and a pin projecting upward from the top of frame member 67, Fig. 3. This spring reduces the load on roller 140 during oscillation of the basket 108 and also reduces the load on the mechanism for raising and lowering the basket when this mechanism is in operation, as will subsequently be described.

The mechanism for driving shaft 112 from motor 73 to spin the basket 108 will now be described. This mechanism includes parts mounted on the plate 120, Figs. 1 and 5, which is attached to the motor by means of the through bolts which hold the two halves of the motor frame together, somewhat longer bolts being substituted for the bolts which come with the motor. The plate 120 has a central opening through which the motor shaft 95 and a part of its bearing extend.

The reference character 131 indicates a short shaft which has a bearing in the block 129 fixed to plate 120. The pulley 121 is secured to shaft 131 by means of a set screw (concealed by the belt) and the shaft is connected with the shaft 112 by means of a section of flexible shafting 132. The flexible shaft is of the proper length to maintain the pulley 121 in light engagement with the end of block 129. The pulley 122 is mounted on the motor shaft 95. The pulleys 123 and 124 are mounted on the lever 125 which is pivoted on the block 130 by means of a shoulder screw 126. Block 130 is fixed to plate 120. The belt 128 is looped around the pulleys as shown in Fig. 5 and normally is loose, so that the rotation of pulley 122 will not drive pulley 121.

The belt 128 is tightened at the proper time by an arrangement which includes a helical spring 127, the roller 133, and the cam 134. The roller 133 is mounted at the end of lever 125 on a portion thereof which is bent to the rear at right angles as indicated by the dotted line. The cam 134 is adjustably mounted on the link 116 as shown in Figs. 5 and 6, by means of a screw 136. The spring 127 tends to rotate lever 125 in a counterclockwise direction about its pivot 126, but when the apparatus is in the position in which it is shown in Fig. 1 such rotation is prevented by the engagement of a portion of cam 134 by the roller 133. When the motor housing is rotated on its pivot 72 to raise the basket 108, there is a relative movement between cam 134 and the roller 133 which brings the latter into alignment with the cut-out 135 in the cam. This occurs when the basket 108 leaves the fluid in the jar and with the motor housing approximately in a horizontal position and enables the spring 127 to rotate lever 125 and tighten belt 128, roller 133 descending into cut-out 135 as far as necessary for this purpose. The belt 128 being tight, the pulley 121 is driven by pulley 122 to spin the basket 108, assuming that the motor 73 is running. As the motor housing continues its rotation on shaft 72 to raise the basket 108 above the cover plate 36 the roller 133 rides up on another portion of cam 134 to loosen the belt and again disconnect the drive.

It will be convenient now to describe the mechanism for rotating the motor housing on shaft 72 to raise and lower the basket 108. This mechanism is partly shown in Figs. 1 and 3 but can best be explained with reference to Figs. 7 to 11, inclusive.

The disc 145 is rigidly mounted on the shaft 72 by means of the hub 146. The disc has three

projecting cams 147, 148, and 149. The stud 151 has a section 152 of reduced diameter which extends through a hole in the side 75 of the motor housing. The section 152 is threaded to receive the nut 154 by means of which the stud is rigidly secured to the housing. The stud 151 has another section 153 of reduced diameter on which the arm 150 is pivotally mounted as shown. Arm 150 has a downwardly extending part which is bent as shown in Fig. 11 to provide a laterally offset part 155 on which the roller 156 is mounted as shown. At the right hand end of arm 150 there is a short cylindrical member 157, which has a section of reduced diameter extending through a bearing hole in arm 150. The end of this section may be riveted outside a washer which is provided, whereby member 157 is rotatably mounted on arm 150. The member 160 is rotatable on shaft 71. The screw 158 extends through a hole in member 157 and is threaded into a tapped hole in member 160. The helical spring 159 surrounds the screw 158 and is compressed between member 157 and member 160. The member 157 can slide on screw 158 by further compressing spring 159 but the spring is quite stiff and in the normal operation of the machine such movement does not take place.

In Fig. 7 the parts of the raising and lowering mechanism are shown in the position which they have in Fig. 1, where basket 108 is immersed in the fluid in jar 20. The dotted line 165 represents the axis of the shaft of motor 73 which along with the motor housing is rotatable on shaft 72. The stud 153 is fixed to the motor housing, this fixed relation being indicated by the dotted line 166. The roller 156 on arm 150 is adjacent the periphery of the disc 145 but not in contact therewith.

Assuming that the motor 73 is running, the disc 145 is rotating slowly in the direction of the arrow thereon and eventually the cam 147 reaches and engages the roller 156. The continued rotation of the disc and cam now exerts a downward pressure on the shaft 71, said pressure being applied through the roller 156, arm 150 and its pivot at 152, member 157, spring 159, and member 160 on shaft 71. The spring 159 cushions the engagement between cam 147 and roller 156 but does not yield appreciably thereafter, and since shaft 71 is fixed against downward movement, the pressure thereon exerted by the cam 147 through arm 150 causes the entire motor housing assembly to rotate in a clockwise direction on shaft 72.

The direction of rotation is indicated by the arrow associated with stud 153 in Fig. 8, this stud being used as a convenient reference point. In Fig. 8, the stud and motor housing are rotating in the direction of the arrow about shaft 72 as an axis and the housing and motor have reached a substantially horizontal position, as indicated by the position of the dotted line 165. The roller 156 has moved away from the disc 145 somewhat, but is still engaged by the cam 147.

As the rotation of stud 153 and the motor housing continues beyond the Fig. 8 position, the subassembly which includes member 157, screw 158, and member 160 begins to rotate in a counterclockwise direction on shaft 71, with the result that the roller 156 moves farther away from disc 145. As the parts are shown in Fig. 9, the roller 156 has moved far enough so that cam 147 is able to pass the roller and no longer exerts any downward pressure on it. The motor housing has now reached the limit of its rotation on shaft 75

72 and is in its highest position, as indicated by the position of the dotted line 165. The motor housing remains stationary in this position momentarily while the cam 147 is passing dead center.

As the rotation of disc 145 and cam 147 continues, the roller 156 rides down the sloping rear face of the cam, permitting the stud 153 and motor housing to rotate rapidly in a counterclockwise direction. This movement is depicted in Fig. 10, where the parts are approaching their lowermost position, as indicated by the position of the dotted line 165. As the downward movement continues, the roller 149 on shaft 141 engages the projection 70, Fig. 1, and the movement is arrested, the parts having resumed the position in which they are shown in Fig. 7, except that cam 147 has passed beyond roller 156. The time interval for the complete cycle is about 15 seconds.

As previously mentioned the horizontally rotatable frame 55 is urged to rotate in a clockwise direction, Fig. 2, by the spring 65, but is restrained against rotation by means engaging the notch 48 in rim 47. This means comprises the downwardly extending pin or stud 170 mounted on the lever 172. The lever 172 is pivoted at 174 on the extension 176 of the bracket 171 which extends across the frame 55 and is secured to the lower edges of the sides 57 and 58 thereof by means of screws, as shown in Figs. 2 and 3. As seen in Fig. 2, the lever 172 is slotted where the pivot 174 passes through it and is urged to move along the pivot by the spring 175 which is tensioned between the adjacent end of the lever and a pin fixed to the bracket 171. Spring 175 is a rather light spring, however, and the more powerful spring 65 maintains the parts in the position in which they are shown, the pivot 174 engaging the end of the slot in lever 172 and the pin 170 on the lever engaging the wall of the notch 48 in the rim 47.

The lever 172 is operated to release frame 55 by means of a lost motion device on shaft 71 which will now be described. This device comprises a metal strip bent to the shape of an inverted U and having holes in the sides 177 and 178 through which the shaft 171 extends, a short cylindrical member 181 adjustably fixed on the shaft by means of a set screw, and a pin 179 which extends through member 181 near the outer circumference thereof and parallel to shaft 71. These parts are shown in Fig. 3 and on an enlarged scale in Fig. 12. The side member 178 has an extension arm 180 the lower end of which is disposed adjacent the end of lever 172, as shown in Figs. 2 and 3.

When the motor housing is rotated on shaft 72 in the manner described the link 116 is rotated also, due to the connection between the motor housing and the link at 104, 99, and 117. The link 116 rotates about the axis of shaft 71 but since the link is fixed to the shaft, the latter is rotated in a clockwise direction as seen in Fig. 12 and rotates member 181 carrying the pin 179. This rotation is ineffective during the greater part of the movement of the motor housing but shortly before the parts have reached their Fig. 9 position the pin 179 on member 181 engages the side members 177 and 178 and thereby causes the extension arm 180 to rotate the lever 172 on its pivot 174. The rotation of lever 172 releases the frame 55 by moving the pin 170 out of notch 48, whereupon the spring 65 starts to rotate the frame in a clockwise direction about

the post 62. The parts are adjusted so that the release of the frame takes place after the basket 108 has been raised out of jar 20 and above the cover plate 36 but before the upward movement has been entirely completed.

When the frame 55 is released as described, the spring 175 moves the lever 172 longitudinally along the pivot 174 as far as the slot in the lever will permit, which is far enough to enable the end of the lever to clear the arm 180 and permit the arm to go by as the upward movement of the basket 108 continues. The spring 175 also tends to rotate the lever 172 on its pivot 174, with the result that when the frame 55 has rotated 90 degrees the pin 170 falls into notch 49 and the rotation of the frame is arrested at that point. The engagement of pin 170 with the side of notch 49 moves lever 172 along its pivot 174 against the tension of spring 175 until the end of the lever engages the side of arm 180. Shortly after this takes place the parts reach their Fig. 9 position and then begin to descend, the link 116 rotating shaft 71 in a counterclockwise direction as seen in Fig. 12. As the parts arrive approximately at their Fig. 10 position the pin 179 on member 181 engages the side members 177 and 178 above center and the continued rotation of shaft 71 restores arm 180 to the position in which it is shown in Fig. 2. The lever 172 then completes its longitudinal movement along the pivot 174 so that the end of the lever is again operatively related to arm 180 as shown. This final movement of lever 172 permits a slight further rotation of the frame 55, but such further movement is insufficient to appreciably affect the positional relation between the basket 108 and the jar 21 in which it is now located.

It will be noted that the spring 175 is effective to substantially reduce the shock which results when the rotation of frame 55 is arrested by engagement of the pin 170 in notch 49, and thereby prevents any damage to the parts concerned. The shock may be further reduced by making the arm 180 somewhat flexible, which will also eliminate most or all of the slight further rotation of the frame referred to in the preceding paragraph.

The lever 172 projects outside the frame 55 through a slot in the side wall 58, so that it can be operated by hand whenever necessary or desirable.

The electrical wiring will now be described with reference to Figs. 1, 4, and 13.

The plug 188 and socket 189 are mounted on the base 10 behind the wall 14 of the tank as shown in Fig. 4. Current is supplied to the plug 188 by means of a socket 186 and the two conductor cord 184, the latter terminating in a plug (not shown) which can be inserted in any convenient socket wired for 115 volt commerical current. The switch 25, heater 23, and thermostatic switch 24 are connected to the terminals of the plug 188 in series. Switch 25 also supplies current to socket 189. This switch may conveniently be mounted on the rim 16 at the front of the machine.

The two conductor cord 185 terminates in the plug 187 which is normally inserted in socket 189. In Fig. 4 both plug 187 and socket 186 have been removed to expose the socket 189 and plug 188 with which they cooperate, respectively. The cord 185 extends upward through a slot in the flange 35, through the short piece of conduit 190 which is fixed in a hole in cover plate 36, and thence in a loop to the grommet 191 through 75

which it passes to the interior of the motor housing. In Fig. 1 the cord 185 is shown as being broken off just inside the housing, to avoid concealing other parts. However, it extends to the right beneath the cover 78, past the flange 38, around inside the end 77 of the housing, where it may be secured by suitable clips (not shown), and thence through an opening in the end 59 of frame 55 to terminals on the switch 26. The other terminals of the switch are connected to the motor 73 by conductors extending beneath the shaft 71.

The switch 25 is the main switch and is operated by hand to turn the machine on and off. The switch 26 controls the circuit of motor 73 and is actuated automatically by means of the upwardly projecting lugs 192 and 193 on the cover plate 36 responsive to rotation of the frame 55. The lug 192 opens the switch, while lug 193 closes it. In order to prevent any danger of damage to the switch 26 when the frame 55 is rotated in a counterclockwise direction a stop is provided, comprising a rubber block 194 mounted on a bracket 195 which is secured to the cover plate 36 by a screw 196. A similar stop may be provided to limit rotation of the frame 55 in the other direction. However, it is preferable to provide a small curved metal member 197 which is secured to the rim 47 by means of a screw and makes the notch 51 deep enough so that the frame cannot be released from this position by accidental operation of lever 172.

The machine and parts thereof having been described, the operation of the machine in cleaning the parts of a watch movement, for example, will now be explained.

It may be assumed that the jars 20, 21, and 22 have been filled about half full with the desired cleaning and rinsing fluids and that the tank 13-14, has been partly filled with water, as mentioned in the previous description. At this time the frame 55, and the motor housing stand in a position in which they are rotated 270 degrees in a clockwise direction from the position in which the frame is shown in Fig. 2, the frame being held against further rotation by notch 51. This is the starting position, also the drying position. The switch 26 has been opened by engagement of its actuating member with the projecting lug 192. The motor housing is in its extreme elevated position, indicated in Fig. 9, being supported in this position by cooperation of cam 149 with roller 156. The cam disc 145 is rotated 180 degrees from the position in which it is shown in Fig. 9. The basket 108 is above the opening 45 in the cover plate 36. The opening 53 in disc 52 is aligned with opening 45 and the other openings 42, 43, and 44 in the cover plate are closed by said disc. This feature prevents accidental contamination of the fluids in the jars when the machine is idle and also tends to prevent loss of fluid by evaporation.

The operator may now close the switch 25 to start the machine, which energizes the heater 23 to heat the tank and the water contained therein. The water circulates around and under the jars and heats the jars and fluids contained therein to the desired temperature, which is maintained at a substantially constant value by the thermostatic switch 24. A temperature of 125 degrees F. has been found to give very satisfactory results. The thermostatic switch is adjustable and may be set for different temperatures over a considerable range.

When the machine has warmed up sufficiently,

11

the operator may remove the basket 108 and place the watch parts therein, after which the basket is replaced. The operator then rotates the motor housing and frame 55 in a counterclockwise direction by means of handle 90 on cover 78 until the frame engages the stop 194, whereupon the pin 170 drops into notch 48 and locks the frame in this position. Disc 52 rotates with frame 55 and uncovers the opening 42 above jar 20. The rotation of the frame tensions the spring 65, and also closes the switch 26 by engagement of its actuating member with the projecting lug 193. The operator may now leave the machine and attend to other duties.

The closure of switch 26 starts the motor 73, which rotates the shafts 84 and 72 as previously explained. The rotation of shaft 72 advances the cam disc 145 with the result that cam 149 moves past roller 156 and the basket is quickly lowered through the opening 42 in the cover plate and into the jar 20. The roller 140 is now in engagement with the projection 70 on frame member 68, and since shaft 84 is rotating, the basket 108 is oscillated up and down in the cleaning fluid contained in jar 20.

The machine is now in the position in which it is shown in Fig. 1, which may be referred to as the cleaning position. It remains in this position for an interval which is determined by the spacing of cams 149 and 147 and the rate at which the cam disc 145 is rotated. In the machine described this interval is about 2 minutes, or a little more.

The cleaning operation is terminated when cam 147 engages the roller 156 to rotate the motor housing on shaft 72 as previously described in connection with Fig. 8. When the rotation starts the roller 140 moves away from projection 70 and the oscillatory motion of the basket 108 ceases. The rotation of the motor housing on shaft 72 raises the basket 108 and when the basket arrives at a position in which it is above the cleaning fluid but is still in the jar 20 the roller 133 on lever 125 reaches the cutout 135 in cam 134, thereby permitting lever 125 to tighten the belt 128 and start spinning the basket 108. During this operation the basket is rotated at high speed to throw off the cleaning fluid from the basket and the parts contained therein by centrifugal force, and since the operation starts while the basket is still well within the jar no substantial amount of fluid is lost. The spinning operation stops when the basket begins to emerge through the opening 42, or shortly thereafter, due to the movement of roller 133 out of the cutout 135, but by this time substantially all the cleaning fluid will have been thrown off to drain back into the jar.

Shortly before the motor housing reaches its Fig. 9 position, and when the basket 108 has been raised entirely above the cover plate 36, the arm 180 operates the lever 172 to release the frame 55, whereupon the spring 65 rotates the frame 90 degrees and it again becomes locked by the engagement of pin 170 with the notch 49. The disc 52 rotates with the frame, covering the opening 42 in the cover plate 36 and exposing the opening 43 above the jar 21. The cam 147 on cam disc 145 then passes the roller 156 and the basket 108 is quickly lowered into the jar 21. This jar contains a rinsing fluid and the position now occupied by the basket 108 may be referred to as the first rinsing position. It will be noted that when the basket 108 is lowered into the jar the spinning drive will again be connected momentarily but this does no harm.

12

The roller 140 is now in engagement with the projection 70 and the basket 108 is oscillated up and down in the rinsing fluid in jar 21. This rinsing operation continues for about one minute, or until the cam 148 on disc 145 engages the roller 156, whereupon the basket 108 is raised out of jar 21 in the same way that it was previously raised out of jar 20. During the upward movement of the basket the spinning drive is again connected to throw off the surplus rinsing fluid.

When the basket 108 has been raised above the cover plate 36, the arm 180 again actuates the lever 172 to release frame 55, which rotates another 90 degrees and becomes locked by engagement of the pin 170 with the notch 50. The disc 52 rotates with the frame, covering the opening 43 and uncovering the opening 44 above which the basket 108 is now positioned. The cam 148 now passes the roller 156 and the basket is lowered into the jar 22. This is the second rinsing position.

The roller 140 cooperating with projection 70 now oscillates the basket 108 up and down in the rinsing fluid in jar 22, the operation continuing for about one minute. The operation is terminated when the cam 149 engages the roller 156 to raise the basket 108 from the jar 22. During the upward movement of the basket the spinning drive is connected as before to throw off the rinsing fluid from the basket and parts contained therein.

When the basket has been raised above the cover plate, the arm 180 actuates lever 172 as before to release the frame 55, which thereupon rotates 90 degrees further and becomes locked by the engagement of pin 170 in notch 51. Disc 52 rotates with the frame to cover opening 44 and uncover opening 45. The rotation of the frame causes the actuating member of the switch 26 to engage the projecting lug 192 on the cover plate, which opens the switch and stops the motor 73. At this time the motor housing and basket are in their uppermost or Fig. 9 position, and the cam 149 is on dead center with respect to roller 156. The cam 149 is preferably a few degrees wider than the other cams and has a flat end which allows for some coasting of the motor before it completely stops.

The machine is now in drying position. The watch parts in the basket have been substantially freed of rinsing fluid by the spinning of the basket as it was raised in the second rinsing position, and the parts having been thoroughly warmed by their progress through the machine, the remaining fluid is quickly evaporated. The drying of the parts is facilitated by a current of warm air which now pours up through the opening 45 in the cover plate from the chamber 28. This opening has been closed throughout the preceding operation of the machine, so that the air in chamber 28 has become heated to the temperature of the tank.

After allowing sufficient time for the parts to become dry, the operator will take the basket off and remove the parts. The drying position is also the starting position and if more parts are to be cleaned they are put in the basket, the basket is replaced, and the machine is started again by rotating the motor housing and frame 55 to their Fig. 2 position, whereupon the described operations of cleaning, rinsing and drying are repeated. Otherwise the machine is shut off by opening the switch 25.

While a certain concrete embodiment of the in-

vention has been described, this has been done to facilitate the understanding thereof and it will be understood that modifications may be made without departing from the principles of the invention. I do not, therefore, wish to be limited to the precise form of the invention shown and described herein, but desire to include and have protected by Letters Patent all forms and modifications of the invention which come within the scope of the appended claims.

I claim:

1. In a machine for cleaning watch parts and the like, a main container, a plurality of jars in said container disposed on a circle, a cover plate for said container and jars, said plate having openings in alignment with said jars, a closure member in the form of a thin plate resting on said cover plate and closing all said openings except one, said member having an opening therein aligned with one of said openings in the cover plate, a frame rotatably supported at the center of said circle, cleaning mechanism mounted on said frame, means for intermittently rotating said frame to position said cleaning mechanism above said jars successively, and an operative connection between said frame and closure member to rotate the latter each time the frame is rotated, whereby the opening in the closure member is successively aligned with openings in said cover plate and said jars are rendered successively accessible to said cleaning mechanism.

2. In a machine for cleaning watch parts and the like, a plurality of individual containers for cleaning and rinsing fluids, a tank in which said containers are disposed and adapted to contain water or other fluid to transmit heat to said containers, an electrical heating element mounted on said tank to heat the same and the water contained therein, a thermostatic switch in circuit with said heating element to maintain the tank and water temperature at a desired constant value, means normally covering said containers to prevent a loss of heated fluid by evaporation, washing mechanism including a basket for parts, means for operating said mechanism to cause said basket to enter said containers successively, said covering means including a device for uncovering said containers one at a time, and means for operating said device in timed relation to the operation of said washing mechanism to uncover each container prior to the entrance of said basket therein.

3. In a machine for cleaning watch parts and the like, a tank, a partition dividing said tank into two compartments, one compartment adapted to contain water and the other constituting a chamber for heating air, a plurality of jars in said water compartment arranged in the arc of a circle, means for heating said tank, a cover for said tank having openings therein aligned with said jars, said cover also having an opening above said air chamber, a closure member supported on said cover and spanning said openings, said member having an opening therein located at the same radial distance from the center of said circle as the openings in said cover, and means for rotating said member about the center of said circle to align the opening therein with the openings in said cover successively.

4. In a machine for cleaning watch parts and the like, a plurality of fluid containers disposed on the arc of a circle, a frame above said containers, means supporting said frame for rotation about a vertical axis at the center of said circle, a second frame, means supporting said second

frame on said first frame for rotation about a horizontal axis, a motor mounted on said second frame, a parts basket supported on said second frame and depending therefrom in radial alignment with said containers, mechanism driven by said motor for rotating said second frame on its axis to lower said basket into a first one of said containers and to subsequently raise the basket therefrom, control mechanism for repeating the lowering and raising operations, mechanism driven by said motor when said basket is in lowered position to oscillate said second frame on its axis, and mechanism controlled by said motor responsive to each raising operation to rotate the said first frame to position said basket above the next container, whereby said basket is lowered into and raised from said containers successively.

5. In a machine for cleaning watch parts and the like, a plurality of fluid containers disposed on the arc of a circle, a frame, a support at the center of said circle on which said frame is rotatable in a horizontal plane, a second frame pivotally mounted on said first frame, a parts basket mounted on said second frame in radial alignment with said containers, a motor mounted on said second frame, mechanism driven by said motor for rotating said second frame on its pivot to lower said basket into one of said containers and to raise the basket therefrom,

20 25 30 35 40 45 50 55 60 65

means tending to rotate said first frame, latching means for holding said first frame against rotation, and means actuated by said mechanism when said basket is raised for releasing said latching means to permit rotation of said first frame to thereby advance said basket to the next container.

6. In a machine for cleaning watch parts and the like, a plurality of fluid containers disposed on the arc of a circle, a support at the center of said circle, a frame mounted on said support for rotation in a horizontal plane, a parts basket mounted on said frame in radial alignment with said containers, means for rotating said frame to position said basket above the first of said containers, a spring tensioned by such rotation, latching mechanism for holding said frame in said position, there being a fixed stop cooperating with said mechanism, a motor mounted on said frame, means driven by said motor to periodically release said latching mechanism, and a plurality of additional stops arranged concentric with said circle and at angular distances equal to the distances between containers, whereby upon successive releases of said mechanism the resulting rotation of said frame and basket is arrested by cooperation of said mechanism and successive stops to position said basket above the remaining containers successively.

7. In a machine for cleaning watch parts and the like, a plurality of fluid containers disposed on the arc of a circle, a frame above said containers, means supporting said frame for rotation about a vertical axis at the center of said circle, a second frame, means supporting said second frame on said first frame for rotation about a horizontal axis, a parts basket supported on said second frame at the same radial distance from the center of said circle as said containers, means for rotating said first frame to position said basket above said containers one after the other, including means for holding said first frame in each position, and means effective in each position for rotating said second frame on its axis to lower said basket into

15

the associated container and raise it therefrom. 8. A machine as claimed in claim 7, including a motor mounted on said second frame and supplying power to rotate the second frame on its axis, and mechanism driven by said motor to control rotation of said first frame.

9. A machine as claimed in claim 8, wherein said first frame is rotated by hand in one direction to position the parts basket above the first container and is rotated in the opposite direction to positions above and beyond the other containers under control of said motor driven mechanism, said machine including a switch for controlling the circuit of said motor, and means responsive to rotation of said first frame in said two directions, respectively, to close and open said switch.

10. In a machine for cleaning watch parts and the like, a frame, a motor mounted on said frame, means pivotally supporting said frame for rotation by gravity about a horizontal axis, a parts basket supported on said frame and depending therefrom, a fluid container supported beneath said parts basket, mechanism driven by said motor to control rotation of said frame to lower said basket into said container, a shaft rotatably mounted on said frame and driven by said motor, means effective to arrest the lowering movement of said basket when the same becomes immersed in the fluid in said container, and mechanism responsive to rotation of said shaft to oscillate said frame on its axis to thereby produce an oscillatory movement of said basket in said fluid.

11. In a machine for cleaning watch parts and the like, a frame, a motor mounted on said frame, means pivotally supporting said frame at one end thereof for rotation about a horizontal axis, a parts basket supported on said frame at the other end and depending therefrom, a fluid container supported beneath said parts basket, mechanism driven by said motor for rotating said frame on its axis to lower said basket into said container, a shaft rotatably mounted on said frame, a roller eccentrically mounted on said shaft, a fixed stop engaged by said roller to arrest the downward movement of said frame and basket when the same is lowered into said container, and a driving connection through which said motor rotates said shaft to oscillate said frame on its axis and move said basket up and down in the fluid in said container.

12. In a machine for cleaning watch parts and the like, a frame, a motor mounted on said frame, means pivotally supporting said frame at one end thereof for rotation about a horizontal axis, a parts basket supported on said frame at the other end for rotation about a vertical axis, a fluid container supported beneath said parts basket, mechanism driven by said motor for rotating said frame on its axis to lower said basket into said container, said mechanism being effective after a predetermined time to rotate said frame in the opposite direction to raise said basket from said container, a driving connection between said motor and said parts basket, said connection including a clutch, and mechanism effective in an intermediate position of said basket to operate said clutch to thereby cause said motor to spin said basket.

13. In a machine for cleaning watch parts and the like, a frame, a motor mounted on said frame, means pivotally supporting said frame at one end thereof for rotation about a horizontal axis, a bracket pivotally supported on said frame at

the other end thereof, a parts basket rotatably supported on said bracket and depending therefrom, a fluid container supported beneath said parts basket, mechanism driven by said motor for rotating said frame on its axis in two directions to lower said basket into said container and raise it therefrom, means for maintaining said basket in a vertical position during the lowering and raising thereof, said means comprising a link pivotally connected at one end to said bracket and having a fixed pivot at the other end adjacent the pivot for said frame, the pivots at opposite ends of said frame and the pivots at opposite ends of said link defining a parallelogram, means including a clutch for transmitting power from said motor to said basket to rotate the same, and mechanism actuated in response to relative motion between said frame and link during the raising of said basket from said container to engage said clutch.

14. In a machine for cleaning watch parts and the like, a frame, a second frame rotatably mounted on said first frame, a shaft rotatably mounted on one of said frames, said shaft and said second frame having the same axis of rotation, a parts basket supported on said second frame, a motor mounted on said second frame, a coupling through which said motor drives said shaft, an element connected to the first frame, and mechanism responsive to rotation of said shaft to cause said second frame to exert a downward pressure on said element to thereby rotate itself on said axis to raise said parts basket.

15. In a machine for cleaning watch parts and the like, a frame, a second frame pivotally mounted on said first frame by means of a horizontal shaft having bearings in both frames, a motor mounted on said second frame, a parts basket supported on said second frame and depending therefrom, a fluid container supported beneath said basket, a connection through which said motor drives said shaft, and mechanism actuated by rotation of said shaft to rotate said second frame thereon in two directions to thereby lower said basket into said container and raise the basket therefrom.

16. In a machine for cleaning watch parts and the like, a frame, a second frame pivotally mounted on said first frame by means of a horizontal shaft having bearings in both frames, a motor mounted on said second frame, a parts basket supported on said second frame and depending therefrom, a fluid container supported beneath said basket, a connection through which said motor drives said shaft, a cam mounted on said shaft, means including said cam normally supporting said second frame and basket in an elevated position, said means being effective upon starting of said motor to rotate said second frame and thereby lower said basket into said container, and means including an additional cam on said shaft operative to rotate said second frame in the opposite direction to thereby raise said basket from said container.

17. In a machine for cleaning watch parts and the like, a frame, a shaft rotatably mounted in said frame, a second frame pivotally mounted for rotation about the axis of said shaft, a motor mounted on said second frame, a shaft coupled to said motor and driven thereby, a parts basket supported on said second frame and adapted to be lowered and raised by rotation of the motor driven shaft, lowering and raising mechanism for said basket operatively connected to said second frame, cam means on said motor driven shaft

for operating said mechanism, and a fluid container mounted on said first frame into and out of which said basket is lowered and raised by operation of said mechanism.

18. In a machine for cleaning watch parts and the like, a frame, a shaft rotatably mounted in said frame, a second frame pivotally mounted on said first frame for rotation about the axis of said shaft, a motor mounted on said second frame, a coupling through which said motor drives said shaft, a parts basket supported on said second frame and adapted to be lowered and raised by rotation thereof, a cam on said shaft and rotated thereby, a jointed link comprising two members pivotally connected to the first and second frames, respectively, a roller on the second said member in the path of said cam when said basket is in lowered position and movable away therefrom by relative movement of said members when the basket is raised, a front face on said cam cooperating with said roller to raise said basket, and a sloping rear face on said cam cooperating with said roller to lower said basket.

19. In a machine for cleaning watch parts and the like, a frame, a shaft rotatably mounted in said frame, a second frame pivotally mounted on said first frame for rotation about the axis of said shaft, a motor mounted on said second frame, a parts basket supported on said second frame to be raised and lowered by rotation thereof, a coupling through which said motor rotates said shaft in the direction in which second frame is rotated to lower said basket, a cam on said shaft having front and rear working faces, mechanism operatively connected to said frames and operated by the front face of said cam to create a mutually repulsive force between said frames effective to rotate the second frame in the direction to raise said basket, and means included in said mechanism and responsive to said last mentioned rotation to shift the said mechanism relative to said cam, thereby rendering the rear face of said cam effective to cooperate with said mechanism to control rotation of said second frame in the direction to lower said basket.

20. In a machine for cleaning watch parts and the like, a frame supported for rotation about a vertical axis, a second frame pivotally supported on said first frame for rotation about a horizontal axis, a plurality of fluid containers disposed in the arc of a circle having its center on said vertical axis, a parts basket supported on said second frame above said containers and at the same radial distance from said vertical axis, a motor mounted on said second frame, a shaft rotatably supported on said first frame and driven by said motor, a timing member mounted on said shaft and carrying a plurality of cams, mechanism controlled by said cams to rotate said first frame at intervals to position said basket above said containers successively, and mechanism operated by said cams to lower said basket into each container as the basket arrives thereat and to raise the basket from each container after a predetermined time.

21. In a machine for cleaning watch parts and the like, a tank adapted to contain water or other liquid, an electrical heating element for heating said tank and liquid, a thermostatic switch in circuit with said heating element to maintain the tank and liquid temperature at a desired constant value, a plurality of upright jars disposed in said tank to be heated by immersion in the liquid in said tank, said jars being arranged in a

circle, a cover for said tank cooperating with the walls thereof and the walls of said jars to form a substantially closed space above the liquid in said tank, said cover having openings therein

5 aligned with said jars, a closure member resting on said cover and adapted to close said openings, said member having an opening therein located at the same radial distance from the center of said circle as the openings in said cover, and means for intermittently rotating said member about said center to position the opening therein above the openings in said cover successively.

22. In a machine for cleaning watch parts and the like, a frame, a parts basket supported on said frame, a fluid container disposed beneath said basket, mechanism operative to impart movements to said frame in opposite directions to lower said basket into said container and raise it therefrom, mechanism operative to impart a 10 vibratory movement to said frame while the basket is inside said container, a motor mounted on said frame and partaking in said movements, and mechanical connections through which said motor drives both said mechanisms.

23. In a machine for cleaning watch parts and the like, a fluid container, a frame, a parts basket, means including a shaft supporting said basket on said frame above said container, means supporting said frame for rotation about a horizontal axis, mechanism on said frame operative to rotate the frame on said axis in two directions to thereby lower said basket into said container and raise it therefrom after a predetermined time interval, a motor mounted on said

30 frame and having a driving connection to said mechanism, and a driving connection between said motor and shaft completed by the rotation of said frame in the direction which raises said basket.

24. In a machine for cleaning watch parts and the like, a fluid container, a frame, a parts basket, means including a shaft supporting said basket on said frame above said container, a support for said frame, mechanism comprising 45 parts on said frame and support operative to move said frame relative to said support to thereby lower said basket into said container and raise it therefrom, a motor mounted on said frame and movable therewith, a driving connection between said motor and said mechanism, a driving connection between said motor and said shaft, a clutch included in said last connection, and means actuated responsive to the said movement of said frame to connect and disconnect said clutch.

25. In a machine for cleaning watch parts and the like, a horizontally disposed base member, a plurality of fluid containers arranged on said member in the arc of a circle, a support mounted for rotation about a vertical axis passing through the center of said circle, a spring for rotating said support, means for latching said support in a plurality of positions corresponding to said containers, respectively, a parts basket mounted on said support, mechanism operative to impart downward and upward movements to said parts basket adapted to lower the same into and raise the same out of one of said containers, and means responsive to upward

70 movement of said basket to unlatch said support to effect movement thereof to its next position by said spring, whereby the continued operation of said mechanism causes said basket to be lowered into and raised from said containers successively.

26. A machine having means for immersion cleansing of parts in a succession of baths, said means including a mechanism having a motor and mounted centrally of the baths, said mechanism being provided with a support upon which the mechanism is mounted for oscillation on a horizontal axis and rotation on a vertical axis, an arm extending laterally of the mechanism and having a parts basket mounted rotatably thereto, and connections between the motor and the mechanism for sequential actuation of the oscillatory and rotatable motion of the mechanism and arm to sweep the arm and basket in a succession of immersions of the basket, the sequence being controlled by control devices positioned to be actuated according to the oscillatory position of the mechanism.

27. The machine of claim 26 wherein the connections for sequential motion include means for a succession of modified oscillatory movements when the arm is in basket immersing position.

28. The machine of claim 26 wherein the con-

5

nctions for sequential motion include means powered by the motor for rotating the basket when the arm is in position to hold the basket immediately above a bath.
